UNITED STATES PATENT OFFICE

HUGH STEWART BROWN, OF HARVEY, ILLINOIS

TAMPING APPARATUS

Application filed September 30, 1926. Serial No. 138,712.

This invention relates to an improvement in reciprocating tools, such, for example, as rock drills, tampers and machines of kindred type which can be handled and controlled by a single operator.

One of the objects of the present invention is to provide a vibratory type of tool which is light in weight, simple in construction and efficient in operation.

10 A further object of the invention is to provide a vibratory type of tool in which there is no rigid connection between the striking part of the tool and casing, thereby eliminating the vibration through the casing and requiring less amount of power to operate the tool.

15 A further object of the invention is to provide a vibratory type of tool in which the operating parts of the tool, as well as the motor, can be completely encased in a dust proof casing.

20 A further object of the invention is to provide a vibratory type of tool with a novel rocker drive and buffer spring construction which reduces the amount of vibration transmitted to the casing to a minimum.

25 A still further object of the invention is to provide an improved vibratory type of tool in which the intensity of the vibration of the tool may be increased or diminished by varying the pressure against the work.

These and other objects are accomplished by providing a construction and an arrangement of various parts in the manner herein-after described and particularly pointed out in the appended claims.

Referring to the drawings:

Fig. 1 is a side elevational view partly in cross section showing the construction of my improved vibratory tool.

Fig. 2 is a top plan view partly in cross section of the vibratory tool shown in Fig. 1.

Fig. 3 is a cross sectional view taken on the line 3—3 of Fig. 1.

Fig. 4 is a detail side elevational view of the rocker member; and

Fig. 5 is an end elevational view of the same.

In the preferred embodiment of my invention herein illustrated, the housing or

casing 10 which incloses the operating parts of the reciprocating tool is preferably made in two sections 11 and 12 secured together by bolts 13 extending through ears formed integrally with adjacent contacting portions of the housing members. The housing member 12 is provided with an upwardly extending sleeve 14 which is adapted to receive and have secured therein a pipe 15, the upper end of which is provided with a suitable handle 16. The lower end of the housing member 12 is provided with a downwardly extending sleeve or bearing portion 17, the lower end of which is provided with laterally and oppositely projecting lugs 18.

One of the important features of my novel vibratory tool construction comprises the employment of means whereby the vibratory or striking action of the movable parts within the casing are directly transmitted to the reciprocating tool and the reciprocating tool is so connected to the casing that the vibratory or reciprocating movement transmitted to the tool is prevented to a considerable extent from being transmitted to the casing. This mechanism comprises a reciprocating anvil 19 which is reciprocally mounted within the bore of the sleeve 17. The anvil 19 is provided with a socket 20 which is adapted to receive therein a tool 21, such as a drill

25 or tamping tool. The lower end of the anvil 19 is provided with an annular flange 22 and immediately above the flange with an anvil plate 23 secured to the anvil preferably by being welded thereto. The anvil is yieldingly or resiliently supported and limited in its reciprocatory movement within the bore of the sleeve 17 by two pairs of compression springs 24 and 25 respectively mounted on suitable studs 26 threaded into the lugs 18 formed on the lower end of the sleeve 17.

The springs 24 are compressed between the bottoms of sockets 27 formed in the lower end of the lugs 18 and the upper side of the anvil plate 23 through apertures in which the studs 26 extend, as clearly shown in Fig. 1. The springs 25 are disposed between the lower side of the plate 23 and the nuts 28 which in turn are secured against displacement by lock nuts 29.

As the result of the described construction the springs 25 and 24 are readily accessible for inspection, removal or replacement, without opening the casing, and, similarly, the 5 degree of compression of said springs can be readily modified to suit varying conditions by merely adjusting the nuts 28 and 29.

From the above description it will be seen that the anvil, together with the tool, is yieldingly or resiliently connected to the casing so that the vibration transmitted to the casing as the result of the impacts of the hammer against the anvil will be reduced to a minimum.

15 Formed integrally with and extending across the interior of the housing member 12 is a pedestal web supporting portion 30 which is reinforced by webs 31 which are arranged at right angles with respect to the portion 30. Secured to the pedestal supporting portion 30 by means of bolts 32 is a pedestal or bearing bracket 33. The pedestal 33 is provided with a main bearing portion 34 in which is mounted a rotary shaft 35 provided 20 at one end with a crank 36. A flange 37 on the shaft engaging one end of a bearing bushing 38 mounted within the bearing portion 34 of the bracket 33 absorbs end thrust. Secured to the other end of the shaft 35 is a sprocket 25 wheel 39 driven by a chain 40 from a sprocket 41 secured to the shaft 42 of an electric motor 43. The electric motor 43 is secured to one side of the housing member 12 by means of bolts 44. The chain 40, and the sprocket 35 30 41 mounted on the shaft of the motor are completely encased in a dust proof casing formed as an extension 46 of the casing member 12. Formed integrally with the bearing bracket 33 is a boss 47 having a bore 48 extending therethrough in which is mounted a shoulder stud 49 locked therein by a nut 50 threaded on the end of the shoulder stud. Pivotally mounted on the enlarged portion 35 40 of the shoulder stud 49 is an oscillating hammer 51. The hammer 51 is provided with an enlarged striking head or weight 52 which is adapted to strike the upper end of the anvil 19 when the anvil is depressed within the path of the hammer. Mounted concentrically with the pivoted end of the hammer and positioned to engage both sides of the pivoted hammer is a rocking or oscillating member 53. The rocking member actuator 53 is provided with spaced apart bearing portions 54 having aligned apertures therethrough which engage with the enlarged bearing portion of the shouldered stud 49, as clearly shown in Fig. 2. The rocking member 53 has a longitudinally extending rectangular bore 55 through which the hammer extends. Formed integrally with and on the free end of the rocking member 53 are two oppositely disposed threaded sleeves 56 adapted to receive the adjustable bolts 57. The inner ends of the threaded bolts 57 have

short pin extensions as shown at 58, on which are mounted two oppositely disposed compression springs 59. The inner ends of the springs 59 engage the opposite sides of the hammer and yieldingly maintain the hammer in operative relation with respect to the rocking member. The rocking member 53 is oscillated about its pivot on the shoulder stud 49 to cause the hammer to oscillate by means of a connecting rod 60 the bearing portion 61 of which is journaled on the crank pin 36 of the shaft 35. The connecting rod is to provide at its other end bifurcated portions 62 provided with transverse aligned bores 63 through which a pin 64 extends for pivotally connecting the rod to a bearing portion 65 formed on the lower side of the rocking member 53.

From the above description it will be seen that as a crank shaft 35 is operatively driven by the motor through the chain 40 and sprockets 39 and 41, the rocking member 53 will be oscillated by the connecting rod 60, thereby causing the hammer to intermittently impact the anvil 19 when by pressure of the tool against the work the anvil is caused to move into the path of oscillation of the hammer head. In order to retard the upward movement of the hammer at the top of its stroke, I have provided a buffer spring 66 which is positioned at such an angle that its lower end will be in a position to be struck by the upper side of the hammer shank 51 near the extremity of its upstroke. The buffer spring is held in position by a stud 67 which is secured to an apertured boss 68 formed integrally with the bearing bracket 33. The stud is provided with a peripheral flange 69. Secured between the flange 69 and the boss 68 is a clamp 70 which is adapted to engage the coils of the spring and support the spring in the position shown in Fig. 1. The lower end of the stud 67 is provided with an extension 71 which extends into the buffer spring 66 and forms a guide for the same.

The operation of the above described device is as follows: Let us assume that the electric motor is thrown into operation causing the chain 40 to operatively drive the shaft 35, which in turn, by reason of the rocking member 53 and connecting link 60, oscillates the hammer 51 about its pivot on the shoulder stud 49. It will be noted that by reason of the springs 59 engaging the opposite sides of the hammer, the hammer will be oscillated under the yielding pressure of these springs and when the anvil 19 and the tool 21 are in the position shown in Fig. 1, the hammer will oscillate without striking the anvil, but when the tool 21 is positioned against the work and the casing depressed with respect to the tool and anvil, thereby compressing the springs 24, the anvil will

be brought within the path of the reciprocating head 52 of the hammer so that the vibratory movement of the hammer will be transmitted to the tool. It will also be noted that by my improved construction the intensity of the vibratory action may be increased in direct proportion to the pressure placed upon the tool against the work.

While I have described one embodiment which my invention may assume in practice, it will, of course, be understood that the same is capable of modification and that modification may be made without departing from the spirit and scope of my invention as expressed in the following claims.

What I claim as my invention and desire to secure by Letters Patent is:

1. In a vibratory tool, the combination with a casing, a helve pivotally mounted for swinging movement in said casing, a motor secured to said casing, a movable tool, means for reciprocating said helve to operate said tool including a crank shaft mounted in said casing, a rocking member pivoted for rocking movement concentrically with the pivot of said helve and a connecting link connecting said crank shaft with said rocking member.

2. In a vibratory tool, the combination with a casing, a helve pivotally mounted for swinging movement in said casing, a motor, a movable tool, means for reciprocating said helve to operate said tool including a crank shaft driven by said motor, a rocking member pivoted for rocking movement concentrically with the axis of the pivot of said helve and having its free end operatively connected to said helve and a connecting link operatively connected to said crank shaft and to said rocking member.

3. In a vibratory tool, the combination with a casing, a helve pivotally mounted in said casing, a motor secured to said casing, a movable tool connected with said casing, means for reciprocating said helve to operate said tool including a crank shaft operatively driven by said motor, a rocking member pivotally mounted in said casing and having the free end thereof resiliently connected to said helve and a connecting link connecting said rocking member and said crank shaft.

4. In a vibratory tool, the combination with a casing, a helve pivotally mounted for swinging movement in said casing, a motor secured to said casing, a movable tool connected with said casing, means including a crank shaft journalled in said casing and operatively driven by said motor, a rocking member journalled in said casing having its free end yieldingly connected to said helve and a connecting link connecting said crank shaft with the free end of said rocking member for operatively driving said helve.

5. In a vibratory tool, the combination

with a casing, a helve pivotally mounted for swinging movement in said casing, a motor secured to said casing, a movable tool connected with said casing, means for reciprocating said helve to operate said tool including a crank shaft journalled in said casing and operatively connected to said motor, a rocking member pivoted so as to rock concentrically with the swinging movement of said helve and having the free end thereof disposed on the opposite sides of said helve and yieldingly connected thereto and a connecting link operatively connecting said crank with the free end of said rocking member.

6. In a vibratory tool, the combination with a casing, a helve pivotally mounted for swinging movement in said casing, a motor secured to said casing, a movable tool connected with said casing, means for reciprocating the helve to operate said tool including a crank shaft journalled to said casing and operatively driven by said motor, a rocking member pivoted to rock concentrically with the swinging movement of said helve and having the free end thereof provided with oppositely disposed springs for yieldingly connecting said rocking member to said helve, and a connecting link operatively connecting said crank shaft with the free end of said rocking member.

7. In a vibratory tool, the combination with a casing, a helve pivotally mounted for swinging movement in said casing, a motor secured to said casing, a movable tool connected with said casing, means for reciprocating the helve to operate said tool including a crank shaft journalled in said casing and operatively connected with said motor, a rocking member pivoted within said casing and having the free end embracing a portion of said helve, two oppositely disposed compression springs adjustably mounted in the free end of said rocking member and engaging the opposite sides of said helve, and a connecting link journalled on said crank shaft and pivotally connected to the free end of said rocking member for operatively driving said helve.

8. In a vibratory tool, the combination with a casing, a helve pivotally mounted for swinging movement in said casing, a motor secured to said casing, a movable tool operatively connected with said casing, means for reciprocating the helve to operate said tool including a bearing bracket secured within said casing, a crank shaft journalled in said bearing bracket and operatively driven by said motor, a rocking member pivoted to said bracket having the free end thereof embracing a portion of said helve, means for yieldingly connecting the free end of said rocking member to said helve, means for adjusting the free end of said rocking member with respect to said helve, and a connecting link

connecting said crank shaft with the free end of said rocking member.

9. In a vibratory tool, the combination with a casing, a helve pivotally mounted in said casing, a motor secured to said casing, a movable tool operatively connected with said casing, means for reciprocating the helve to operate said tool including a bearing bracket secured within said casing, a crank shaft journalled in said bearing bracket and operatively driven by said motor, a rocking member pivoted to said bracket having the free end thereof embracing a portion of said helve, means for yieldingly connecting the free end of said rocking member to said helve, means for adjusting the free end of said rocking member with respect to said helve, and means mounted within said casing and in the path of movement of said helve for buffing the upper movement of said helve.

10. In a vibratory tool, the combination with a casing, a helve pivotally mounted in said casing, a motor secured to said casing, a movable tool operatively connected with said casing, means for reciprocating the helve to operate said tool including a bearing bracket secured within said casing, a crank shaft journalled in said bearing bracket and operatively driven by said motor, a rocking member pivoted to said bracket having the free end thereof embracing a portion of said helve, means for yieldingly connecting the free end of said rocking member to said helve, means for adjusting the free end of said rocking member with respect to said helve, and resilient means secured within said casing and in the path of movement of said helve for buffing the upper movement of said helve.

11. In a vibratory tool, the combination with a casing, a helve pivotally mounted in said casing, a motor secured to said casing, a movable tool operatively connected with said casing, means for reciprocating the helve to operate said tool including a bearing bracket secured within said casing, a crank shaft journalled in said bearing bracket and operatively driven by said motor, a rocking member pivoted to said bracket having the free end thereof embracing a portion of said helve, means for yieldingly connecting the free end of said rocking member to said helve, means for adjusting the free end of said rocking member with respect to said helve, and a buffer spring positioned at an angle with respect to said helve and secured to said bearing bracket for buffing the upper movement of said helve.

12. In a vibratory tool, the combination of a portable casing, a helve pivotally mounted therein, and means for reciprocating said helve including a rocking member pivoted concentrically with the pivot of said helve, a resilient connection between said member and helve spaced from their common pivot, and means for rocking said member.

13. In a vibratory tool, the combination of a casing, a helve pivotally mounted therein, and means for reciprocating said helve including a crank shaft mounted in said casing, means for driving said shaft, a rocking member pivoted concentrically with the pivot of said helve, a resilient connection between said member and helve spaced from their common pivot, and a connecting link between said shaft and member.

14. In a vibratory tool, the combination with a portable casing, a helve pivotally mounted in said casing, a motor secured to said casing, and means for reciprocating said helve including a crank shaft mounted in said casing, a rocking member pivoted concentrically with the pivot of said helve and a connecting link connecting said shaft and member.

15. In a vibratory tool, the combination of a supporting structure, a helve pivotally mounted thereon, and means for reciprocating said helve, including a rocking member pivoted concentrically with the pivot of said helve, a resilient connection between said member and helve spaced from their common pivot, and means for rocking said member.

16. In a vibratory tool, the combination of a supporting structure, a helve pivotally mounted thereon, and means for reciprocating said helve, including a rocking member pivoted concentrically with the pivot of said helve, an adjustable resilient connection between said member and helve spaced from their mutual pivot, and means for rocking said member.

17. A combination such as defined in claim 15 in which an element of said resilient connection is adjustable toward and from said helve.

18. A portable power operated tool comprising, a casing adapted to receive a reciprocating tool and equipped with a manipulating handle, a motor attached to said casing, and means enclosed within said casing and driven by said motor for actuating said tool, said means including a pivoted oscillating member provided with a weighted head, an oscillating actuator yieldably associated with said member to actuate the same, a shaft operatively connected with said motor and provided with a crank, and a connecting rod between said crank and said actuator.

19. A portable power operated tool comprising, a casing adapted to receive a reciprocating tool and equipped with a manipulating handle, a motor attached to said casing, and means enclosed within said casing and driven by said motor for actuating said tool, said means including a pivoted oscillating member provided with a weighted head, and an oscillatory actuator connected with said motor and yieldably associated with said member to actuate the same.

20. A portable power operated tool com-

prising, a casing adapted to receive a reciprocating tool and equipped with a manipulating handle, a motor attached to said casing, an oscillating member pivoted in said casing and provided with a weighted head disposed in operative relation to said tool, an actuator pivotally mounted to oscillate in said casing and yieldably connected to said member, means driven by said motor for positively operating said actuator, and means whereby the inoperative stroke of said weighted head is cushioned.

21. A portable power operated tool comprising, a casing adapted to receive a reciprocating tool and equipped with a manipulating handle, a motor attached to said casing, a weighted head for actuating said tool by impact, an oscillatory member pivoted in said casing for moving said head back and forth in a predetermined path, means for producing a cushioning effect upon the inoperative stroke of said head and an actuator positively driven from said motor for yieldably actuating said oscillatory member during the operative stroke of said head.

22. A portable power operated tool comprising, a casing adapted to receive a reciprocating tool and equipped with a manipulating handle, a vibrating weighted head adapted to actuate said tool by impact, means for cushioning the movement of said head away from said tool and positively driven power operated means for yieldably urging said head toward said tool.

35 In witness of the foregoing I affix my signature.
